UNITED STATES PATENT OFFICE

2,204,408

CONNECTOR PLUG

Elwood E. Folsom, Trumbull, Conn., assignor to
General Electric Company, a corporation of
New York

Application September 18, 1937, Serial No. 164,513

5 Claims. (Cl. 173—363)

The present invention relates to connector plugs such as are used on cord sets for connecting heating devices and the like to a current source.

5 One object of the invention is to provide an improved plug structure wherein the cord is firmly anchored in the plug body and wherein a strain relief is provided for the connection between the conductors and the plug contacts so that a pull on the cord will not put a strain directly on such connections.

10 A further object of the invention is to provide an improved construction of plug contact which is simple to manufacture and to which the conductor is connected without the use of screws.

15 Further objects and the advantages of the invention will be pointed out in the following specification.

20 For a consideration of what I believe to be novel and my invention, attention is directed to the following specification and the claims appended thereto.

25 In the drawing, Fig. 1 is a top view of a plug embodying my invention, a portion of the plug body being broken away; Fig. 2 is a top view of the connector plug with the upper half of the plug body removed; Fig. 3 is a longitudinal sectional view of the plug; Fig. 4 is a perspective view of one of the plug contacts, and Fig. 5 is a top view of the two contacts with the strain relief member molded thereon.

30 Referring to the drawing, the plug comprises a plug body or housing formed of two complementary halves 6 and 7 fastened together by a suitable means such as rivets 8. The plug body is formed from a suitable molding compound, such as phenolic condensation product and a suitable filler, capable of withstanding the temperatures met with. It may be formed from any of the molding compounds now in use for connector plugs of this type. At its forward end, the plug body is provided with two longitudinally extending pockets 9 and 10 in which are located 35 the clamping ends or sockets 11 of the two contacts 12, and at its rear end with a transversely extending pocket 13 in which are located the ends of the contacts to which the conductors 14 are connected. Pockets 9 and 10 are connected 40 to pocket 13 by two longitudinally extending passages 15 and 16 which are of less depth than the pockets 9, 10 and 13. Contacts 12 have relatively long shanks 17 which are located in passages 15 and 16. At their inner ends contacts 45 12 are provided with heads 18 to which the con-

ductors 14 are connected. Communicating with pockets 9 and 10 are end wall openings 19 through which contact posts or blades enter to engage the contacts 11. Communicating with pocket 13 is a passage 20 through which the cord 5 21 enters the plug body.

As best shown in Fig. 4, each contact comprises two strips of suitable metal having central portions in engagement to form the shanks 17. At one end, they are grooved transversely to 10 provide head 18 and to form a transverse passage in which the end of the conductor 14 is located. At the other end, they are curved longitudinally, flared out at the ends, and cut away to form tongues 22 to provide the clamping ends 15 or sockets 11. The two strips are fastened together by spot welding as indicated at 23 and 24. By varying the position of the spot weld 23 with respect to the socket 11, the spring pressure of the socket walls can be adjusted, the 20 pressure increasing as the spot weld is moved toward the socket and decreasing as it moved away from the socket. The spot weld 24 is located at the head 18 and serves to attach the conductor 14 to the contact as well as to hold the 25 two strips together. The two strips are alike and in the assembling operation, it is necessary merely to place the end of the conductor 14 between the two strips at the one end and then simultaneously spot weld the strips at the two 30 points indicated. This serves to form a satisfactory contact which can be manufactured at low cost and wherein the conductor is connected to it without the use of screws and without a separate operation. Also, it provides a contact 35 wherein the tension of the jaws of the socket can be given the desired value by merely changing the location of the spot weld.

After the two conductors have been connected to the two contacts, the two contacts are assembled in correct spaced relation to each other in a suitable fixture and a body 25 of suitable insulating material, such as rubber or the like, is molded directly around the heads 18, the ends of the conductors 14 and the adjacent portion 45 of the cord 21. This serves to anchor the connections between the conductors and the contacts in the insulating body 25 and also to provide a strain relief for the connections. The body 25 is of a size and shape to fit in pocket 13 and it will 50 be clear that any pull on cord 21 will be taken by the body 25 engaging the wall of pocket 13. Also, the body holds the cord against twisting. Preferably, the adjacent portion of the cord 21 has material molded around it for quite some 55

length as indicated at 27, the outer end tapering as shown at 28, thus providing protection against sharp bending of cord where it enters the plug body.

- 5 In use, a connector plug of this type is subjected often to fairly high temperature, the contact sockets 11 sometimes reaching temperatures of the order of 500 to 600 degrees F. This is a temperature higher than the rubber or similar material in which the heads 18 are embedded could withstand, and the purpose of the relatively long shanks 17 between the sockets 11 and the heads 18 is to serve to dissipate heat and prevent the high temperature of the socket portion of the contact from being transmitted to the head portion thereof. By the use of a relatively long shank 17, I am enabled to dissipate a large amount of heat and thus maintain the temperature at heads 18 at a safe low value.
- 15 20 To further cut down the transfer of heat from sockets 11 to heads 18, I provide openings 30 in the shanks. This serves to decrease the cross-sectional area of the shanks and thus minimize the travel of heat through the shanks from the contact sockets to the heads. With an arrangement of this kind, I have been able to keep the temperature at the heads 18 where the molded body 25 is located at a value of the order of 170 degrees F., a temperature which rubber is able 25 30 readily to withstand.

A pair of contacts 12 with the conductors of the cord 21 attached to the heads thereof and the body 25 molded thereon is shown in Fig. 5. This forms a unitary structure wherein the body 25 carries the two contacts 12 and which can be handled as a unit. And in no way can the connections between contacts and the cord be disturbed or become detached. To assemble a plug, it is necessary merely to place a molded unit between two body members 6 and 7 with the sockets 11 in pockets 9 and 10 and the body 25 in pocket 13 and fasten the body members together. Since the connection between the conductors and the contacts is a permanent one and protected from breakage by molded body 25, the two body members 6 and 7 can be permanently fastened together by rivets. This is of advantage in that the fastening together can be done at low cost and, being permanently fastened together, the 40 45 50 plug cannot be tampered with. As will be seen from Figs. 1 and 2, the pockets 9, 10 and 13 are slightly larger than the parts which fit in them so that the contacts can float to a limited extent to permit of connection to posts or contact blades which may be out of alignment somewhat.

What I claim as new and desire to secure by Letters Patent of the United States is:

1. In a socket construction for use in a connector plug, two elongated flat strips of metal having flat shank portions in engagement with each other, said strips having walls forming grooves at one end of the shank portions to receive a conductor and being flared outwardly at the other end to form spaced contacts providing a socket, a weld on said wall portions connecting the strips and conductor together, and a second weld on said flat shank portions adjacent the flared contact portions, securing the strips together and placing said contact portions under tension upon insertion of a connector into said socket.

2. In a socket construction for use in a connector plug, two elongated flat strips of metal having flat shank portions in engagement with each other, said strips at one end of the shank portions being disposed around a conductor and being flared outwardly at the other end to form spaced contacts providing a socket, a weld on said strips at the portions surrounding the conductor connecting the strips and conductor together, and a second weld on said flat shank portions adjacent the flared contact portions securing the strips together and placing said contact portions under tension upon insertion of a connector into said socket.

3. In a socket construction for use in a connector plug, two elongated flat strips of metal having flat shank portions in engagement with each other, an opening formed in the shank portions of each strip reducing the cross-section thereof, said strips having walls forming grooves at one end of the shank portions to receive a conductor and being flared outwardly at the other end to form spaced contacts providing a socket, a weld on said wall portions connecting the strips and conductor together, and a second weld on said flat shank portions adjacent the flared contact portions securing the strips together and placing said contact portions under tension upon insertion of a heating appliance connector into said socket, said elongated shanks of reduced cross-section dissipating the heat from said connector and preventing it from reaching the connection to said conductor.

4. In a socket construction for use in a connector plug, two elongated flat strips of metal having flat shank portions and being flared outwardly at one end to form spaced contacts providing a socket for receiving a connector prong of an electric heater, the other ends of said shank portions being fused together and connected to the bared end of an insulated conductor, a weld on said flat shank portions adjacent the flared contact portions securing the strips together and placing said contact portions under tension upon insertion of the connector prong into said socket and an opening formed in each shank portion to reduce the cross-section thereof whereby the heat from the electric heater conducted along said shanks from the socket to the connection with said conductor is dissipated to prevent damage to said connection.

5. In a socket construction for use in a connector plug, two elongated flat strips of metal having flat shank portions and being flared outwardly at one end to form spaced contacts providing a socket for receiving a connector prong of an electric heater, the other ends of said shank portions being fused together and connected to the bared end of an insulated conductor, said flat shank portions being fused together at a second point adjacent the flared contact portions whereby said contact portions are placed under tension upon insertion of the connector prong into said socket, each shank having a portion of reduced cross-section located between the fused portions whereby the heat from the electric heater conducted along said shank from the socket to the connection with said conductor is dissipated to prevent damage to the insulation on said conductor.

ELWOOD E. FOLSOM.
